UNITED STATES PATENT OFFICE.

ROBERT I. BLUMBERG, OF NEW YORK, N. Y., ASSIGNOR TO THE WAY CO. INC., OF NEW YORK, N. Y., A CORPORATION OF NEW YORK.

OIL-GAS BURNER.

1,162,558.

Specification of Letters Patent. Patented Nov. 30, 1915.

Application filed September 11, 1915. Serial No. 50,231.

To all whom it may concern:

Be it known that I, ROBERT I. BLUMBERG, a citizen of the United States, and a resident of the city of New York, Flushing, borough of Queens, in the county of Queens and State of New York, have invented a new and Improved Oil-Gas Burner, of which the following is a full, clear, and exact description.

10 This invention relates to heating apparatus and has particular reference to appliances for burning liquid fuel.

Among the objects of the invention is to provide an improved device for use in all makes or styles of stoves, heaters, ranges, furnaces and boiler heaters, means being provided to convert the present heating appliances, where coal, coke, wood or the like are used, into fuel oil burners with a corresponding economy of fuel cost and increase of convenience and efficiency.

Another object of the invention is to provide a burner adapted for the use of all kinds or grades of oils and especially the cheaper and unrefined varieties of oils, the device being found in practice well adapted for the burning of cheap distillates from gas factories or the like.

With the foregoing and other objects in view, the invention consists in the arrangement and combination of parts hereinafter described and claimed, and while the invention is not restricted to the exact details of construction disclosed herein, still for the purpose of illustrating a practical embodiment thereof reference is had to the accompanying drawings, in which like reference characters designate the same parts in the several views, and in which—

40 Figure 1 is a perspective view showing the main parts of the device in operative position, the second diffuser being omitted; Fig. 2 is a vertical longitudinal section on the line 2—2 of Fig. 3; Fig. 3 is a vertical transverse section on the line 3—3 of Fig. 2; Fig. 4 is a plan view with the air drums and diffusion members removed and showing the auxiliary air pipe in horizontal section; and Fig. 5 is a sectional detail on the line 5—5 of Fig. 2.

Referring now more particularly to the drawings, I show a rigid base 10 of cast metal

or the like and shown herein as of substantially rectangular form. This base is provided at its ends with vertical openings 11 through which air is supplied to the combustion chamber from beneath the base. The main portion of the base surrounding these openings comprises a vertically arranged rim having on its inner wall an inwardly projecting rib 12. The rib, however, merges into the vertical end walls 13 of a centrally disposed oil well 14 having a closed bottom and bounded on its ends and sides by said walls 13 and the main rim of the base. The lower portion of the rim serves to support the burner device as a whole at sufficient elevation above the stove or other heater grate to provide ample flow of air through the grate and through the openings 11. The upper edge or portion of the rim in connection with the rib 12 provides seats for the air drums 15, the lower edges of the drums resting upon the ribs and requiring, therefore, no bolts, screws or other fastening devices to hold them in position.

At 16 is a cup having a central vertical nozzle 17. The cup is located in the oil well 14 and into the lower end of the nozzle is fitted an oil supply pipe 18 projecting through the bottom of the oil well as shown in Fig. 2. This pipe 18 constitutes a means, therefore, for holding the cup securely in position. The nozzle 17 is preferably shorter than the height of the cup and the oil delivered into the cup is ignited, and the cup becoming heated causes the vaporization of the oil, the vapor becoming mixed with air passing upwardly through the openings 11. The cup is formed with a notch 16' at one side whereby any excess or overflow of oil from the nozzle filling the cup will flow into the well outside of the cup and will be consumed therein without wasting or danger. Liquid fuel may be delivered to the pipe 18 through another pipe 19 from any suitable source of supply and controlled by any well known means, such features not being illustrated.

The air drums above referred to are shown herein as two in number and of triangular prismatic form, each having a sloping upper wall 15^a and triangular side walls 15^b. As already set forth, the lower edges

of the walls 15^a and 15^b rest within the rim of the base and upon the rib 12. The inner edges of the side walls 15^b are vertical and fit snugly against the outer surfaces of the walls 13. Each air drum also includes a narrow horizontal lip 20 at the top extending across toward the corresponding lip of the other member. A diffusion plate 21 extends from one lip 20 to the other. This plate 21 is provided with rabbeted ends fitting snugly upon the edges of the lips and is strengthened by a strap 22 of a hinge pivoted at 23 to one of the lips 20. The opposite end of the strap 22 is adapted to nest snugly between a pair of lugs 24 on the other lip whereby the plate 21 is effectively held in position.

The structure between the air drums and beneath the diffusion plate 21 is practically open above the base rim whereby openings 25 are formed on the two sides of the structure and through which openings the products of combustion emerge. The primary combustion takes place beneath the diffusion plate 21 at the place where the fresh air admitted upwardly through the air drums mixes with the vapor formed with the vaporization of the oil in or about the cup 16. The plate 21 being hinged as indicated provides for free access to the cup and nozzle for any purpose such as igniting or initiating the operation of the burner. Either or both of the air drums 15, however, may be removed from the base, if desired, at any time.

Under certain conditions depending upon the character of oil employed or other circumstances, an auxiliary fresh air supply is provided, and it comprises a vertical pipe 26 fitted in the base preferably through the bottom of the oil well and having a horizontal perforated pipe 27 secured to its upper end. The perforations are indicated at 27' and 27'' on the inner side and bottom respectively. The air delivered upwardly through the pipe 26 being in close proximity to the main flame is heated and jets forcibly laterally through the ports 27' for mixing with the flame or products of combustion on the opposite side of the burner. The air through the series of ports 27'' mixes with the products of combustion on the near side of the burner. This auxiliary air augments the intensity of the heat and renders it impossible for any fuel value to be wasted.

At 28 is indicated another diffuser supported upon legs 29 having feet 30 resting upon the inclined walls 15^a of the air drums and hence bent at an angle to the main portions of the legs. The diffuser 28 is in the nature of a plate slightly concaved or depressed in its center. All of the combustion takes place below this diffuser and the heat and other products of combustion are de-

flected laterally so as to be well dispersed and hence brought into contact with a large area to be heated.

I claim:—

1. In a burner of the class set forth, the combination of a rectangular base, an oil well supported by the base between its ends leaving air passages between the well and the ends, each of said air passages being surrounded by a supporting rib, a pair of triangular prismatic air drums supported upon said ribs at the ends of the base and having upwardly directed top walls inclined toward each other, the upper ends of the inclined walls being spaced upwardly above the edges of the oil well, means connecting said upper ends of the air drum walls, and means to deliver liquid fuel into the oil well.

2. In a burner of the class set forth, the combination of a base, an oil well secured to the base at its central portion, there being open air spaces between the oil well and the ends of the base through which air is passed upwardly, a pair of air drums supported upon the base and having open lower ends communicating with said air passages, said air drums being converged toward each other at their upper ends and forming with the walls of the oil well restricted passages for the air moving upwardly therethrough, and a movable diffusion plate supported upon the upper ends of the air drums forming beneath the plate and between the air drums a combustion chamber, substantially as set forth.

3. In a burner of the character set forth, the combination of a rigid base having an integral oil well of rectangular form secured at the central portion thereof and having oppositely arranged vertical end walls extending above the sides of the frame, an oil cup and nozzle within the oil well and below the plans of the tops of said end walls, a pair of triangular prismatic air drums seated upon the ends of the base and having open ends abutting against said walls and leaving restricted air spaces between the upper edges of the end walls and the tops of the drums, a diffusion member extending from the top of one drum to the top of the other drum forming therebeneath a combustion chamber, and an auxiliary air supply extending upwardly through the base serving to draw air from below the burner and deliver the same in jets at both sides of the combustion chamber.

4. In a burner, the combination of a frame, oil feeding devices at the central part of the frame, there being open air spaces at the ends of the frame, a pair of air drums supported upon the ends of the frame and having open bottoms and inner sides communicating with said air spaces and directing the air upwardly and inwardly over the

oil feeding devices, means connecting the air drums forming therebeneath a combustion chamber, auxiliary air supply means leading from beneath the frame above the combustion chamber, said air supply means being functional to deliver the air to both sides of the combustion chamber, and a con-

caved diffusion plate supported upon the air drums and occupying a position above the auxiliary air supply means.

ROBERT I. BLUMBERG.
